UNITED STATES PATENT OFFICE.

ALBERT P. DANNER, OF BRIDGEPORT, CONNECTICUT.

CHRISTMAS-TREE HOLDER.

Application filed March 14, 1927. Serial No. 175,147.

The present invention relates to new and useful improvements in stands or holders for Christmas trees, flag staffs or other objects which it is desired to hold in a vertical position.

For its objects the invention has the providing of a holder or stand for the purpose stated which is readily foldable and thus made portable; which employs a minimum number of different parts; which may be employed equally well with heavy or light objects; which more tightly engages an object the heavier it is; and which since it employs a minimum number of different parts may be manufactured at low cost.

An additional object is to provide a holder of the character stated which is self-operating as to grasping an article placed in it and which will readily release such article when the same is withdrawn in the usual manner.

A further object is to provide a holder which will automatically adjust itself to receive and hold vertically tree trunks, flag staffs or the like of different diameters.

With the foregoing and other objects in view, as will become apparent as the description proceeds, the invention resides in certain novel features of construction, combination and arrangement of parts herein-after more fully described in connection with the accompanying drawing and pointed out in the claims hereunto appended.

In said drawing:—

Fig. 1 is a perspective view of my holder showing the same in operative position, a fragment of a tree-trunk, staff or the like being shown in dotted lines to make clear the operation;

Fig. 2 is an elevational view of the holder with the parts in folded position; and

Fig. 3 is a plan view showing the parts in operative position ready to receive an object to be supported.

Referring to the drawing, wherein the reference characters indicate corresponding parts in the several views, the holder has three equally spaced supporting legs, each indicated by the numeral 5. These legs are of identical shape and construction. By having the legs all duplicate I can secure quantity production at small initial tool cost. In this connection it is pointed out that while I have shown and described but three supporting legs this is only by way of example since any number more than three

may be used if desired. However, in practice I find three legs to be sufficient.

In addition to the legs 5 the holder includes a sectional pivoting or retaining ring or member shown as made up of three identical sections 6. Pivotedly mounted between the adjacent out-turned ends 7 of the sections, on the rivets, bolts or the like 8 connecting such ends, are identical biting, or gripping, supporting members 9, of which three are shown. The upper and lower end portions of members 9 are inclined inwardly as shown for a purpose to be described. The upper ends of members 9 are sharpened or pointed as at 10 to bite or dig into the tree trunk or the like. Somewhat similarly and for the same purpose the lower ends of said members are sharpened to provide the knife-like portions 11.

For the purpose of economy and simplification the upper ends of legs 5 are pivoted on the rivets 8. The lower ends of the legs are curved outwardly to provide ground-engaging or foot portions 12. When the parts are in the positions shown in Figs. 1 and 2 and weight, as a Christmas tree, is placed on the holder the legs 5 tend to spread and turn about their pivots. Such action is prevented by engagement of the upper end portions 13 of the legs with the portions of the ring sections 6 immediately adjacent to the outturned ends 7.

While the members 9 are pivoted between the ends of sections 6, the legs 5 are pivoted to the outside of said sections. Owing to this arrangement movement of the legs about the rivets will not cause similar movement of members 9 and vice versa.

It is believed the operation of the holder will be apparent without further description. However, it is pointed out that, with the holder positioned on the floor for instance and with its legs spread as in Figs. 1 and 3, the tree trunk suggested at 14, will upon being lowered between members 9 first strike the knife-like portions 11 thereof. This will cause the members to move about their pivots and the sharpened upper ends 10 will engage the trunk. Further downward movement of the trunk will cause the portions 10 and 11 to further bite and cut into it and the greater the weight or force on the trunk the tighter the same is held.

Since the members 9 are free to move independent of the legs 5 there is nothing to interfere with their action in gripping the

tree trunk. Moreover since these members are free of the legs the tree may be more readily withdrawn from the holder. This is true since the biting action does not take 5 place owing to the tendency of the legs to spread. Further with the biting portions inclining upwardly as shown there is practically no resistance to movement of the tree out of the holder by a movement longitudinally away from the latter.

A holder such as I have invented is used only at stated intervals and hence it is desirable that it be folded into a small space for storage. This is provided for in the 15 present instance since the legs 5 may be folded toward each other to provide a compact structure as shown in Fig. 2. As the holder will often times be sold attached to a tree this feature is additionally desirable. The 20 tree in most such cases will have its branches tied into the trunk and the holder will not project to get in the way.

In view of the fact that there are but three parts of different construction used 25 in the holder I am able to effect a great savings when "tooling up" for mass production. The legs are of duplicate construction as above stated and this same is true of the biting members 9 and the ring sections 6. 30 These parts may be of cold rolled steel.

Although the invention has been shown and described in detail reference must be had to the annexed claims for a definition of its limitations.

35 What is claimed is:—

1. In a tree or staff holder, supporting legs, a retaining ring, means pivoting said legs to the retaining ring at equally spaced points, tree or staff engaging members pivoted to said retaining ring at spaced points and having portions to engage and bite into said tree or staff, and said engaging members being movable independently of said legs.

45 2. In a tree or staff holder, a retaining ring, said ring comprising at least three arcuate sections having their ends offset, means connecting adjacent ends of said sec-

tions, gripping members arranged between said adjacent ends and pivotally mounted 50 on said connecting means and projecting above and below said ring, supporting legs pivotally mounted on said connecting means independent of said gripping members, and said ring acting as a stop to limit turning 55 movement of said legs on their pivots.

3. In a tree or staff holder, a retaining ring, said ring comprising at least three arcuate sections having outturned ends, 60 means connecting adjacent ends of said sections, gripping members arranged between said adjacent ends and pivotally mounted on said connecting means, said members having angularly disposed arms projecting above and below the ring and positioned to engage an elongated article placed within the ring, said members having their upper and lower ends sharpened to bite into such article, and supporting legs pivoted on said connecting means and limited in their pivotal movement by engagement with said ring.

4. In a tree or staff holder, a retaining ring consisting of at least three identical sections, means connecting the ends of said sections, at least three identical supporting legs for said ring, said legs pivoted to the connecting means, and at least three identical tree or staff engaging members pivoted on said connecting means in positions to engage a tree or staff placed within the holder, said engaging members being movable independently of said legs.

5. In a tree holder, a retaining member, gripping members pivoted on said retaining member at equally spaced points and having end portions extending above and below said member for engagement with a tree trunk, supporting legs also pivoted on said member at spaced points, and said gripping members movable independently of said legs.

Signed at Bridgeport in the county of Fairfield and State of Connecticut, March A. D. 1927.

ALBERT P. DANNER.
